ATTORNEY

UNITED STATES PATENT OFFICE

HENRI CHIREIX, OF PARIS, FRANCE, ASSIGNOR TO SOCIETE FRANCAISE RADIO ELECTRIQUE, OF PARIS, FRANCE, A JOINT-STOCK COMPANY OF FRANCE

LOUD SPEAKER

Application filed April 13, 1928, Serial No. 269,654, and in France April 29, 1927.

The present invention relates to apparatus of the kind used for the production, transmission or reproduction of sound, more particularly, to loud-speaking telephones or microphones. Still, more particularly, it concerns among these apparatus comprising a vibrating diaphragm of large surface known as "diffusers".

The invention consists essentially of a particular form of construction of apparatus equipped with marginally unsupported diaphragms whereby the fragility of the latter in handling, use and transportation is eliminated.

Apparatus equipped with large-sized diaphragms are known in the prior art in which the diaphragm presents a perfectly free edge or border, while being supported, at the point where it is acted upon, by the means adapted to cause it to vibrate. In apparatus of this type, the reproduction of sounds is particularly good because deformations due to the fixing or attaching means clamping the edge of the diaphragm more or less firmly against supporting annuli or frames are entirely absent in the reproduction. The only serious drawback they involve is that they are very delicate and sensitive and therefore easily broken when handled or shipped.

Now, the present invention provides apparatus of the said sort wherein the element of fragility is obviated without any attendant inconvenience looked at from the viewpoint of freedom of vibration of the marginal portions of the diaphragm.

This end is realized in the following manner: The diaphragm of the curved or cone type of a definite geometric form (cone, pyramid, paraboloid, etc.) is unsupported and free around its edges; in other words, it is not connected in any way, either elastically or otherwise, with the frame of the apparatus. Indeed, the edge is merely made to bear upon a band or strip of plastic material, such as rubber, or soft felt, preferably, conveniently interposed between the edge of the diaphragm and the body of the apparatus.

The invention will be more readily under-

stood by the aid of the following detailed description and reference to the accompanying drawings showing, by way of example, various embodiments of the basic idea of the invention as applied to loudspeaker apparatus.

In the drawings, Figure 1 illustrates an approved form of the invention; and Figure 2 illustrates a modification thereof in which two diaphragms are employed, the diaphragms being arranged in a suitable housing.

According to Figure 1, an annulus A made from soft rubber, very soft felt, or any similar material is conveniently held in position, for example, inside a grooved metal piece B which is shaped in accordance with the contour of the tympanum. The piece B is supported by means of arms C radially disposed about the casing containing an actuating means such as the casing D in Figure 2. The tympanum or diaphragm of conical form E or of other form (pyramidal or the like) is furnished with connecting means between its apex and the vibrating motor or actuating means, whereby it is held in position.

Figure 2 illustrates a modified form of construction according to which the band made from flexible or elastic material, A, is placed upon a bearing surface formed on the opening of a box or case B' serving as the body of the apparatus. Fixed upon said case B' is also the motor case D by the aid of arms C. It will be noted that the band A may preferably present a certain inclination with reference to the surface of the tympanum E so as to provide a more favorable bearing, it being understood that such a slope could be provided also in the arrangement illustrated in Figure 1. The case B' may moreover be provided upon the other side (not shown in the illustration) with a second opening and a second tympanum actuated by an extension of the rodlet F.

The contact between the periphery of the vibrating diaphragm and the bearing band may be interrupted or discontinuous either by means of breaks or gaps in the band or else because of notches or gaps formed in the circumference of the diaphragm.

The invention, as will be understood, is capable of a great number of modifications in design and application, according to the particular nature of the tympanum, the 5 shape, nature and mode of attachment of the latter, of the band or ring of flexible material, the disposition of the armature or support of the apparatus in relation with the motor and the peripheral band, etc.

10 Having thus described the nature of my invention, what I claim is:

1. An acoustic device comprising a casing, an opening in said casing, a layer of plastic material adjacent the edge of said opening, 15 said layer of plastic material being arranged to have an active face inclined to the plane of the edge of said opening, a supporting member, a driving motor supported by said supporting member, and a large conical dia- 20 phragm supported solely by its operative connection with said driving motor and the contact of its peripheral edge with the inclined active face of said layer of plastic material.
- 25 2. An acoustic device comprising a box like casing, openings in opposite sides of said casing, a layer of plastic material secured to the edge of each opening, each of said layers of plastic material being arranged 30 to have an active face inclined to the plane of the side of said casing, a pair of dia- phragms positioned within said casing with their peripheral edges engaging the inclined faces of said layers of plastic material, a link 35 connecting the apices of said diaphragm, a driving motor supported from one side of said casing, and a driving connection from said driving motor to one of said diaphragms, whereby said diaphragms are supported 40 solely by said driving connection and by their peripheral engagement with said layers of plastic material.
